UNITED STATES PATENT OFFICE

GAY H. BUTLER, OF ATLANTA, GEORGIA

PIPE-COIL HEADER

Application filed December 3, 1927. Serial No. 237,536.

Generically this invention relates to pipe fittings but it is more especially directed to the type of fitting known as a header.

The principal object of this invention is the provision of a sectional header adapted for use in connection with a pipe coil or multiplicity of pipe conduits whereby each pipe is directly connected to an individual section of the header.

10 Another important object of this invention is the provision of a header of this type formed from a plurality of individual sections, each section being directly attachable to a coil section or pipe line and means for 15 uniting the sections into a unitary structure.

A further object of this invention is the provision of a header formed with a plurality of individual detachable sections, relatively adjustable, each section being attachable to a coil section or pipe line at any angle with respect to the other sections, and adjustable means for uniting the sections into a unitary structure.

20 A still further object of this invention is the provision of a sectional header of this character having joint or closure caps at each end of the assembled structure and adjustable means interconnecting said caps for uniting the sections into a unitary structure, said 30 means being operable to permit relative adjustment of any one of the sections with respect to the unitary device.

With these and other objects in view, which will become apparent as the description proceeds, the invention resides in the construction, combination and arrangement of parts, hereinafter more fully described and claimed, and illustrated in the accompanying drawings, in which like characters of reference indicate like parts throughout the several figures, of which:

Fig. 1 is a view in elevation of an apparatus showing my improved header operatively positioned with pipe sections broken away, said sections being shown in fragmentary elevation;

Fig. 2 is a longitudinal section of the header; and

50 Fig. 3 is an elevational view taken at right angles to Fig. 2.

The headers with which I am familiar heretofore in use, especially the one piece type, necessitated the employment of a union or coupling intermediate its length in every line of pipe comprising the coil and installation and subsequent repairs to the device were effected with more or less difficulty. Therefore, it was to overcome the deficiencies of such devices by effecting a saving in material and labor incident to the installation of

55 the header and to render it easy to effect repairs, and so forth, by the provision of a header composed of cooperating individual and relatively adjustable sections, each section being directly attachable to one of the

60 lines of pipe comprising the coil, said pipe having male threads at its extremity for engagement with said section, the section at each end of the device being formed with a

65 detachable closure cap, said caps having central longitudinally aligned openings adapted to receive a tie-rod threaded at its ends for cooperation with exteriorly positioned ad-

70 justing nuts, by which means the several sections are united into a unitary structure and through adjustment of which any of the sec-

75 tions may be expeditiously positioned with respect to the entire device, or secured to or detached from a respective coil pipe as

80 desired, without the necessity of disconnecting other sections or the entire header to effect repairs in connection with a particular coil pipe, that I designed the header forming

85 the subject-matter of this invention.

In the illustrated embodiment characterizing this invention there is shown my im-

proved header A and coil B. The coil B comprises a plurality of water, steam or the like pipes 5 of conventional design. The

90 header A comprises a plurality of tubular-like header sections 6 formed on one side with a raised portion 7 extending beyond the circumferential surface of the section and having a central opening 8 internally threaded as at 9 to receive the threaded extremity of

95 one of the pipes 5, for a purpose which will hereinafter more fully appear. Said sections 6, in the present instance, are formed adjacent each end with collar-like enlargements 10, the inner walls at the ends of each

100

section being inclined to form tapered seats 11 for a purpose hereinafter more fully described.

An inner slip nipple or sleeve member 12 is formed with an enlargement at its center as at 13 and tapering therefrom oppositely to its ends, to form the tapered portions 14, the said nipple or sleeve adapted to bridge the joint formed by the meeting ends of two 10 of the sections, the tapered portions 14 adapted to engage the seats 11 of the respective sections when the nipple is operatively positioned to support said sections in longitudinal alignment. A gasket 15 formed 15 from copper or other suitable material is mounted on the nipple sleeve 12 and is adapted to seat on the enlargement 13 between the meeting ends of sections 6 supported by said nipple, to form a water or 20 steam tight joint when said sections have been operatively positioned, as will herein-after appear.

A closure or joint cap 16 is inserted at each end of the device, and formed with an annular flange 17 adapted to seat against one of the gaskets 15 interposed between the said flange and the end of the section 6 to form a steam or water tight joint, each of said caps 16 being centrally apertured as at 18. 25 A tie rod 19 extends through said apertures and has its ends threaded as at 20 to engage the interior thread of the nuts 21 when operatively positioned thereon, and when brought into engagement with said caps, adapted to 30 draw the sections 6 toward each other compressing the gaskets to form non-leakable joints and to unite said sections into a unitary structure.

It is obvious that any one of the sections 40 may be provided with inlet and outlet openings similar to 22 or additional sections may be added at either end to constitute outlet or inlets similar to the inlet section 23, and which may be positioned at any angle with 45 respect to the device.

It will be noted that the device above described is susceptible of being easily installed and any individual section thereof easily secured in operative position and the entire 50 device united into a unitary structure by simply actuating the nuts 20, thereby drawing the closure or joint caps 16 toward each other simultaneously effecting engagement of the tapered seats with corresponding portions 55 of the slip nipple or nipples dependent upon whether two sections or a multiplicity of sections 6 are employed in the particular instance.

From the above it is apparent that I have 60 designed a header effecting elimination of unions in connecting the coil pipes to the header, thereby decreasing the necessary distance between the coil pipes and rendering 65 the header more compact, while at the same

time enhancing the appearance of the assembled device.

In conclusion, it will be apparent that I have designed a sectional header which may be employed in connection with any number of coil pipes by the simple addition or subtraction of sections, dependent upon the exigencies of the particular requirements. It is capable of a variety of uses, is easily installed as a unitary structure, permits expeditious repairs to any one section or pipe, effects a saving in initial cost by eliminating the necessity for a number of different sized headers, is simple in construction, may be manufactured at a reasonable cost and is efficient for the purposes intended. 70 75 80

Although in practice, I have found that the form of my invention illustrated in the accompanying drawings and referred to in the above description as the preferred embodiment is the most efficient and practical, yet realizing the conditions concurrent with the adoption of my device will necessarily vary, I desire to emphasize that various minor changes in details of construction, proportion and arrangement of parts, may be resorted to within the scope of the appended claims without departing from or sacrificing any of the principles of this invention. 85 90

Having thus described my invention, what 95 I desire protected by Letters Patent is as set forth in the following claim:

A header comprising a plurality of relatively adjustable sections, the interior walls adjacent the ends of each section being formed with tapered seats, internal sleeves insertable within the meeting ends of the sections to bridge such joints, said sleeves being tapered from their centers towards their ends to engage said complementally formed seats, gaskets mounted on said sleeves between the meeting ends of said sections, closures adapted to seat within the ends of the opposite end sections, each closure provided with a circumferential flange, a gasket mounted intermediate the flange and the respective ends of said end sections, and detachable means for forcing the sections up on the sleeves and securing the closures against the ends of the header, whereby a normally unitary and non-leakable 100 105 110 115 120 structure is effected.
